UNITED STATES PATENT OFFICE.

WILLIAM A. DUNLAP, OF PITTSBURG, PENNSYLVANIA.

ATTACHING HANDLES TO VESSELS.

SPECIFICATION forming part of Letters Patent No. 653,863, dated July 17, 1900.

Application filed June 29, 1899. Serial No. 722,233. (No model.)

To all whom it may concern:

Be it known that I, WILLIAM A. DUNLAP, a citizen of the United States, residing at Pittsburgh, in the county of Allegheny and State of Pennsylvania, have invented or discovered certain new and useful Improvements in Attaching Handles to Vessels, of which improvements the following is a specification.

The invention described herein relates to certain improvements in the manner of detachably connecting handles to coffee-pots, &c. In the manufacture of enameled coffee-pots the handle, which is not enameled, must be attached after the body is enameled, and as the enamel coating is easily broken or cracked by blows riveting is impracticable.

This invention has for its object a construction and arrangement of parts whereby the handle may be secured to the body without injury to the enamel-surface.

In the accompanying drawings, forming a part of this specification, Figure 1 is a side elevation of a portion of a coffee-pot having the handle secured thereto in accordance with my improvement. Fig. 2 is a sectional elevation of the same. Fig. 3 is a sectional view on a plane indicated by the line III III, Fig. 2, the ear being detached from the body. Fig. 4 is an elevation of the same parts and a portion of the handle. Fig. 5 is a view similar to Fig. 2, illustrating a modification of my improvement. Fig. 6 is a section on the line VI VI, Fig. 5. Figs. 7 and 8 are detail views illustrating a further modification.

In the practice of my invention I use ears, consisting of a circular body portion 1, provided with extending lugs 2, through which are passed the rivets whereby the ears are secured to the body of the vessel. As shown in the drawings, the lugs 2 are so bent that the body portion 1 of the ears are a sufficient distance away from the body of the vessel to permit the head of the bolt 3 to slip between the ears and the vessel, as shown in Figs. 2, 5, and 8. In order that the head of the bolt may bear centrally on the disk portion 1, the latter is radially slotted, as at *a*, for the reception of the stem of the bolt.

The handle 4 is provided at its end with seats adapted to bear on the body portions of the ears. The stems of the bolts pass through the seats and through openings in the rear thereof. The handles are provided with sockets or countersinks 5 for the reception of the nuts 6, screwing onto the bolts.

In order to prevent the lateral disengagement of the bolts from the ears, a bead or flange 7 projects from the inner surface of the body portions of the ears into a cup-shaped washer 8, which is slipped onto the bolt before the latter is placed in position on the ears. When the nut is screwed onto the bolt, the washer is drawn against the ear, the edges of the washer fitting around the flange on the ear, thereby holding the bolt from lateral movement out of the slot in the ear as long as the nut is screwed up.

In lieu of employing a cup-shaped washer for locking the bolt as against movement out of the slot the body portion of the ears may be cupped or recessed, as at *b* in Figs. 5 and 6, for the reception of the head of the bolt, the slot *a* extending down into the cup or recess. As the slot is only slightly larger than the stem of the bolt, the latter cannot pass out of the slot as long as the bolt-head is held in the cup or recess in the ear.

As shown in Figs. 7 and 8, the bolts will be retained in position if the ears be so attached to the vessel that the slots open in opposite directions. When such construction and arrangement is employed, the handle itself will hold the bolts in engagement with the ears.

I claim herein as my invention—

1. As a means for securing handles to coffee-pots, the combination of a bolt, an ear radially slotted for the reception of the stem of the bolt and means for holding the bolt in engagement with the ear, substantially as set forth.

2. As a means for securing handles to coffee-pots, &c., the combination of a bolt, and an ear having a socket or recess for the reception of the head of the bolt and having a slot of a width less than the diameter of the head of the bolt and extending into the slot or recess, substantially as set forth.

3. The combination of a coffee-pot, radially-slotted ears secured to the pot with the slots opening in opposite directions, a handle and bolts having their stems projecting through the slots and engaging the handles, substantially as set forth.

In testimony whereof I have hereunto set my hand.

WILLIAM A. DUNLAP.
